BATHTUB

Ernst R. Koppel, Kalamazoo, Mich., assignor to
Borg-Warner Corporation, Chicago, Ill., a corporation of Illinois

Application October 10, 1951, Serial No. 16,893

Term of patent 14 years

(Cl. D4—4)

To all whom it may concern:

Be it known that I, Ernst R. Koppel, a citizen of the United States of America, and resident of Kalamazoo, in the county of Kalamazoo and State of Michigan, have invented a new, original, and ornamental Design for a Bathtub, of which the following is a specification, reference being made to the accompanying drawing, forming a part hereof, in which:

Fig. 1 is a perspective view of a bathtub, showing my ornamental design;

Fig. 2 is a front elevation thereof;

Fig. 3 is a fragmentary sectional view taken along the plane of line 3—3 of Fig. 2; and

Fig. 4 is a fragmentary sectional view taken along the plane of line 4—4 on Fig. 2.

The dominant features of the design reside in those portions shown in full lines and stippling.

I claim:

The ornamental design for a bathtub, as shown and described.

ERNST R. KOPPEL.
